UNITED STATES PATENT OFFICE.

LOUIE T. LA PAUGH, OF UTICA, NEW YORK.

OUTLET-BOX.

No. 851,597.

Specification of Letters Patent.

Patented April 23, 1907.

Application filed February 7, 1906. Serial No. 299,957.

To all whom it may concern:

Be it known that I, LOUIE T. LA PAUGH, a citizen of the United States, residing at Utica, in the county of Oneida and State of New York, have invented certain new and useful Improvements in Outlet-Boxes; and I, do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in outlet boxes for electric conduits, and consists in the provision of a novel manner of fastening the cover to the box, involving a saving of labor and material and providing a secure and inexpensive fastening means, doing away with inwardly or outwardly bent ears which are commonly formed upon junction boxes and which are frequently liable to break off.

In order to make steel drawn boxes with ears bent at right angles to the wall of the box, a very ductile and high grade steel must be used, and in so doing, the operation of blanking and drawing a box without heating or reheating, hardens the steel to such a degree that it is very difficult to bend the parts of the box at right angles to the sides without breakage, for the reason that the operation of drawing a box out of one piece of steel will necessarily destroy or weaken the fiber of the metal, thereby weakening the ears at the point of bending, and it is the aim of the present invention to produce a box without any inwardly or outwardly extending lugs, to obviate these objections.

More specifically, the present invention comprises means for fastening a cover to an outlet box comprising posts which have split ends adapted to pass through an aperture in the bottom of the box and be turned in opposite directions, securely anchoring the posts, while the upper ends of the posts are adapted to pass through apertures in the cover and means for holding the cover over the upper ends of said posts.

My invention consists further in various details of construction which will be herein-after fully described and then specifically defined in the appended claims.

I illustrate my invention in the accompanying drawings, in which:

Figure 1 is a perspective view of my improved junction box, showing the cover fastened thereto. Fig. 2 is a cross sectional view through the box and cover. Fig. 3 is a sectional view on line 3—3 of Fig. 2. Fig. 4 is a detail perspective view of one of the fastening posts. Fig. 5 is a perspective view of an outlet box, the upper ends of the posts being split and adapted to be bent over the upper ends of a box cover to hold the same in place. Fig. 6 is a perspective view on line 6—6 of Fig. 5, and Fig. 7 is a perspective view of one of the fastening posts.

Reference now being had to the details of the drawings by letter, A designates an outlet or junction box which, in the present instance, is shown square in outline and provided with the usual plugged openings for the reception of conduits. Said box is provided with apertures A' in the bottom thereof to receive the split ends B of the posts B'. Said posts which may be of any desirable shape or form and which, in the drawings, are shown as rectangular-shaped in cross section, are fastened to the box by the split ends being passed through said apertures and said ends bent at right angles to the length of the posts and clenching the bottom of the box and are preferably located adjacent to the opposite side walls of the box in order not to interfere with the conduits which may be passed through the walls of the box.

D designates the cover of the box which has lugs D' about the edge thereof designed to engage over the edges of the box to hold the same against a lateral movement, and said cover is provided with slots E adapted to receive said posts, as shown clearly in the drawings.

In Figs. 1 and 2 of the drawings, I have shown the posts as provided with apertures N which are adapted to receive the pins K which, after the cover has been placed upon the box, are passed through said apertures and form keys to securely hold the cover in place.

In Figs. 6 and 7 I have shown the two ends of the posts as similarly constructed, each end being split and instead of forming an aperture in the upper end of the post, the split ends B' are turned down over the cover, clenching the upper surface thereof in the same manner as the lugs at the lower end are

2
clenched, thus forming a secure means for holding the cover in place.

From the foregoing it will be noted that by the provision of the means shown and described, a simple and efficient locking mechanism is afforded for securely holding a cover to an outlet box by the utilization of keys passing through the apertured posts or forming the opposite ends of the posts with the split ends which are clenched, respectively, against the bottom of the box or the cover, in the manner shown and described.

What I claim is:—

1. An outlet box having slots in the bottom thereof, posts passing through said slots and fastened to the bottom of the box, a cover having slots to receive said posts, and means for holding the posts in said slots of the cover, as set forth.
2. An outlet box having slots in the bottom thereof, posts passing through said slots and fastened to the bottom of the box, a cover having slots to receive said posts, the upper ends of said posts being apertured, and keys

passing through said apertures and adapted to hold the cover upon the box, as set forth.

3. An outlet box having slots in the bottom thereof, posts having split ends passing through said slots and adapted to be clenched against the bottom of the box, a cover having slots to receive said posts, and means for holding the posts in said slots of the cover, as set forth.

4. An outlet box having slots in the bottom thereof, posts having split ends passing through said slots and clenched against the bottom of the box, a cover, slots therein adapted to receive said posts, and locking pins passing through apertures in said posts and bearing against the outer face of said cover, as set forth.

In testimony whereof I hereunto affix my signature in the presence of two witnesses.

LOUIE T. LA PAUGH.
